ATTORNEY

UNITED STATES PATENT OFFICE.

THOMAS J. HENDERSON, OF COLUMBUS, GEORGIA.

HANGER FOR TROLLEY-WIRES.

1,372,507.

Specification of Letters Patent. Patented Mar. 22, 1921.

Application filed August 7, 1920. Serial No. 401,854.

To all whom it may concern:

Be it known that I, THOMAS J. HENDERSON, a citizen of the United States, residing at Columbus, in the county of Muscogee and 5 State of Georgia, have invented new and useful Improvements in Hangers for Trolley-Wires, of which the following is a specification.

The object of my present invention is the 10 provision of a simple, efficient and durable trolley-wire hanger, and one that is susceptible of ready manipulation for the various connections of which it is capable.

To the attainment of the foregoing the invention consists in the improvement as hereinafter described and definitely claimed.

In the accompanying drawings, hereby made a part hereof:—

Figure 1 is an elevation showing the arrangement of my novel hanger relatively to a trolley-wire, an ear thereon, and a copper feed wire.

Fig. 2 is a similar view with the copper wire and strap omitted, and dead end guy 25 wires connected to the body.

Fig. 3 is a vertical diametrical section of the arrangement in Fig. 1.

Fig. 4 is a section at right angles to Fig. 3.

Fig. 5 is a plan view of the arrangement 30 shown in Figs. 1, 3 and 4.

Fig. 6 is a perspective of the plug.

Similar numerals of reference designate corresponding parts in all of the views of the drawings.

35 Among other elements my novel hanger comprises a body 1. The said body 1 is made, by preference, of malleable iron in the shape shown and is provided with a central pendent threaded stem 2. The upper portion of the body is shaped into an upstanding post 3. The said post 3 is threaded, as indicated by 4, and is bifurcated as indicated by 5, the bifurcation extending down into the body about the proportional distance 45 illustrated.

In addition to the body 1 characterized as described, my novel hanger includes a plug 6, preferably of malleable iron, a nut 7, and a strap 8 of copper or other material compatible with its purpose. The plug 6 is shaped to snugly occupy the bifurcation 5 in the body 1 and is provided with apertured ears 9 and shoulders 10 to bear against opposite sides of the post 3 with a view to preventing endwise shifting or displacement of the plug. The plug 6 is further provided on

the upper edges of its ears 9 with fins 11. These fins 11 are designed when the nut 7 is turned down tight on the ears 9 to coöperate with the lower notched or ratchet face 12 of 60 the nut and thereby preclude casual loosening and displacement of the nut. The strap 8 is of loop form and has its upper arm disposed in the bottom of the bifurcation 5 and held under pressure by the plug 6 while its 65 lower arm is apertured as indicated by 13 to receive the stem 2. The upper arm of the strap 8 terminates in a T-head 14 for the connection of a feed wire of copper or other appropriate material, and the lower arm is 70 designed to be held against the ear 15 of a trolley-wire 16 so as to make a good contact. The apertures in the ears 9 are for the connection of dead end guy wires indicated by 16* in Fig. 2.

In Fig. 1 a feed wire 20 is shown as interposed between the plug 6 and strap 8.

It will be apparent from the foregoing that I have provided a practically advantageous trolley-wire hanger that is well 80 adapted to withstand the rough usage to which trolley-wire hangers are ordinarily subjected and at the same time is so constructed that a feed wire may be electrically connected in approved manner with a trolley-wire, and so that there is no liability 85 whatever of a casual disconnection taking place.

Having described my invention, what I claim and desire to secure by Letters-Pat- 90 ent is:—

1. In a trolley-wire hanger, the combination of a body having a pendent threaded stem for connection to a trolley-wire ear and also having a threaded and bifurcated 95 post, a looped conductive strap having an arm disposed in the said bifurcation and terminating in a T-head, and also having an arm apertured and receiving the stem and adapted to make contact with a trolley-wire 100 ear, a plug arranged in the bifurcation of the post and upon one arm of the strap and having apertured ears and shoulders to bear against opposite sides of the post and also having fins on the outer edges of the ears, 105 and a nut mounted on the post and having indentures at intervals in its inner side to coöperate with the said fins.

2. The combination in a trolley-wire hanger, of a body having a threaded and bifurcated post, a conductive strap resting in 110 said bifurcation, a plug resting in the bifur-

cation and against said strap, and a nut mounted on the post and arranged against the plug.

3. The combination in a trolley - wire hanger, of a body having a threaded and bifurcated post, a conductive strap resting in said bifurcation, a plug resting in the bifurcation and against said strap, and a nut mounted on the post and arranged against the plug; the said plug having apertured ears and fins on the outer edges thereof, and a nut having indentures at intervals at its inner side to coöperate with said fins.

4. In a trolley-wire hanger, the combination of a body having a threaded stem at one end and a threaded and bifurcated post at its opposite end, a looped conductive element arranged with one arm on the stem and its other arm in the bifurcation, a plug arranged in the bifurcation and against the

latter arm of the conductive element, and a nut mounted on the post against the plug.

5. A trolley - wire hanger comprising a body having a threaded stem at one end and a threaded and bifurcated post at its opposite end, a plug seated in the bifurcation of the post, and a nut mounted on the post and arranged to coöperate with the plug. 25

6. A trolley - wire hanger comprising a body having a threaded stem at one end and a threaded and bifurcated post at its opposite end, a plug seated in the bifurcation of the post, and a nut mounted on the post and arranged to coöperate with the plug; the plug having a fin on its outer side and the 30 nut having an indentured inner side to coöperate with said nut. 35

In testimony whereof I affix my signature.

THOMAS J. HENDERSON.
